CASKET LOCK HANDLE

Jon W. Hauser II, St. Charles, Ill., assignor to Elgin
Metal Casket Company, Elgin, Ill.

Filed Jan. 2, 1974, Ser. No. 429,864

Term of patent 14 years

Int. Cl. D8—06

U.S. Cl. D31—11

FIG. 1 is a perspective view of a casket lock handle showing my new design;

FIG. 2 is a front elevational view thereof;

FIG. 3 is a top plan view thereof, the bottom being a mirror image of the top; and

FIG. 4 is a side elevational view, from the left side, the right side being a mirror image of the left side.

The back is plain and unornamented.

I claim:

The ornamental design for a casket lock handle, as shown and described.
